(57) **CLAIM**

The ornamental design of the jewelry setting/gemstone arrangement, as shown and described.

DESCRIPTION

FIG. 1 is a side view of a jewelry setting/gemstone arrangement showing my new design;

FIG. 2 is a perspective bottom view of the jewelry setting/gemstone arrangement of FIG. 1;

FIG. 3 is a perspective top view of the jewelry setting/gemstone arrangement of FIG. 1;

FIG. 4 is a right side view of the jewelry/gemstone arrangement setting of FIG. 1; and,

FIG. 5 is a top view of the jewelry/gemstone arrangement setting of FIG. 1.

The broken lines are provided for illustrative purposes only, and form no part of the claimed design. In addition, the portions of the jewelry setting/gemstone arrangement that are not shown in the drawing do not form any part of the claimed design.

1 Claim, 5 Drawing Sheets
